UNITED STATES PATENT OFFICE

166,323

AIR DIFFUSING OUTLET FOR VENTILATING SYSTEMS

Franz J. Kurth, Mamaroneck, N. Y., assignor to
 Anemostat Corporation of America, New York,
 N. Y., a corporation of Delaware

Application November 28, 1949, Serial No. 6,289

Term of patent 14 years

(Cl. D62—4)

To all whom it may concern:

Be it known that I, Franz J. Kurth, a citizen of the United States, residing at Mamaroneck, in the county of Westchester and State of New York, have invented a new, original, and ornamental Design for an Air Diffusing Outlet for Ventilating Systems, of which the following is a specification, reference being had to the accompanying drawing, forming part thereof.

Fig. 1 is a front elevation of an air diffusing outlet for ventilating systems, showing my new design.

Fig. 2 is a rear elevation thereof.

Fig. 3 is a section on the line 3—3 of Fig. 1.

Fig. 4 is a section on the line 4—4 of Fig. 1.

Fig. 5 is a sectional view taken on the lower, left corner of Fig. 2.

I claim:

The ornamental design for an air diffusing outlet for ventilating systems, substantially as shown.

FRANZ J. KURTH.
